UNITED STATES PATENT OFFICE.

CHARLES SNEIDER, OF NEW YORK, N. Y., ASSIGNOR OF ONE-HALF OF HIS
RIGHT TO DANIEL SLOTE, OF SAME PLACE.

TEMPORARY BINDER.

SPECIFICATION forming part of Letters Patent No. 229,195, dated June 22, 1880.

Application filed April 28, 1880. (Model.)

To all whom it may concern:

Be it known that I, CHARLES SNEIDER, of New York, in the county of New York, and in the State of New York, have invented certain 5 new and useful Improvements in Temporary Binders; and I do hereby declare that the following is a full, clear, and exact description thereof, reference being had to the accompanying drawings, and to the letters of reference 10 marked thereon, making a part of this specification.

The nature of my invention consists in the construction and arrangement of a binder or cover for magazines, sheet-music, or other papers, as will be hereinafter more fully set forth. 15

In order to enable others skilled in the art to which my invention appertains to make and use the same, I will now proceed to describe its construction and operation, referring to the 20 annexed drawings, in which—

Figure 1 is an end view of my binder. Fig. 2 is a longitudinal section thereof. Figs. 3, 4, and 5 are detail views of parts of the same. Fig. 6 is a view of the interior cover. 25

A A represent the main or outside covers, connected by the back B. In the back B is inserted and fastened a sheet-metal plate, C, the ends of which are turned upward and then inward, forming, as it were, grooved projections *aa*, into which the binder D D' (with its supplemental back E, shoulders *b*, hooks *h h'*, and flanges *d*) is to be moved sidewise. 30

D D' represent the inside or auxiliary covers of the binder, connected by the back E, 35 and the cover D' is provided along three of its edges with flaps D², having suitable tying-strings, so that the papers attached in the binder can be entirely inclosed, if desired.

At each end of the supplemental back E is 40 fastened a sheet-metal plate, F F', which is struck up, as shown, forming two parallel shoulders or offsets, *b b*, and leaving at the outer end a flange, *d*, which comes flush with the edge of the back. The cover D is cut off at 45 each end the width of this flange, so that the ends will be flush with the outer shoulders or offsets, *b*. The inside cover can then be inserted from one side under the grooved projections *a* of the plate C, attached to the outside cover,

thus securing the two together, while at the same time the inside cover can be easily and quickly removed when desired. 50

In one of the plates, F, of the inside cover are fastened a number of long hooks, *h*, which project through the shoulder or offset at one end and extend inward over the raised portion of the plate, the end of each hook being slightly bent upward. In the other plate, F', are an equal number of similar hooks, *h'*; but these latter hooks are not stationary. The 60 under arm of each hook *h'* is elongated and passes through perforations in the two shoulders *b b*, and the extreme inner end is either bent or enlarged, so that the hook cannot be pulled out entirely, but only a certain distance. 65

In attaching a magazine or any other doubled paper the hook *h'* is drawn out and the middle of the paper slipped under the corresponding stationary hook *h*, after which the hook *h'* is pushed in again, so as to come in 70 the middle of the paper at the bottom, thus holding the paper in place.

When sheet-music or other single sheets of paper are to be fastened the hooks *h h'* are provided with sheet-metal clamps *i*, which are 75 made by simply doubling a piece of sheet metal around each hook. The edge of the paper is then inserted between the two plates of metal, which hold it sufficiently firm.

This invention is applicable for binding magazines and other papers, music, &c., for scrapbooks, indexes, and many other purposes where temporary binding is desirable. 80

Having thus fully described my invention, what I claim as new, and desire to secure by 85 Letters Patent, is—

1. In a temporary binder, the cover D D', provided with metal plates F F', having shoulders or offsets *b b*, a series of stationary hooks, *h*, in one plate, and a series of movable hooks, *h'*, in the other plate, substantially as herein set forth. 90

2. In a temporary binder, the series of stationary hooks *h* and the series of movable hooks *h'*, and a sheet-metal clamp, *i*, attached 95 to each hook, as described, for the purpose of binding or holding single sheets, substantially as herein set forth.

3. In a temporary binder, the combination of the cover D D', provided with flaps D², shouldered plates F F', having, respectively, stationary and movable hooks h h', and forming flanges d d, and the exterior cover, A, with plate C, forming grooved projections a a, substantially as and for the purposes herein set forth.

In testimony that I claim the foregoing I have hereunto set my hand this 22d day of 10 April, 1880.

CHAS. SNEIDER.
